[57] CLAIM

The ornamental design for a drafting and measuring tool, substantially as shown and described.

DESCRIPTION

FIG. 1 is a front elevational view of a drafting and measuring tool showing my new design;

FIG. 2 is a typical side elevational view thereof;

FIG. 3 is an enlarged cross-sectional view thereof as taken from line 3—3 of FIG. 1, shown broken away for ease of illustration.

The rear, not shown, is flat, plain and unornamented.

FIG 2

FIG 3
